DEVICE AND A PROCESS FOR CONTROLLING THE CRIMPING ARC IN COMPRESSION CRIMPING OF STRANDS OF FIBERS

Harry Wegener, Ems, Switzerland, assignor to Inventa A. G. fuer Forschung und Patentverwertung, Zurich, Switzerland

Application May 27, 1954, Serial No. 432,812

Claims priority, application Switzerland May 28, 1953

5 Claims. (Cl. 19—66)

The present invention relates to a process for controlling the crimping arc in compression crimping of a strand of fibers, and a device therefor.

Compression crimping has recently been used on a large scale for the production of imitation wool from staple fiber. In the known processes, the compression crimping of fiber strands or cables for spinning, however, does not result in a definite crimping for each fibril present in the strand determined by the arc number per cm., but the arc numbers vary within a certain range.

The variation of the crimping number over the above mentioned range is, with given adjustment, generally a function of the crimping pressure. The crimping pressure is not a constant during the operation, since it depends on various factors, such as fluctuations of the titre, changes in the moisture content of the strand, etc.; the crimping number has, therefore, to be regularly tested. The crimping pressure is then regulated manually according to the test results. The high rates, at which strands are moved in modern processing, require very short test intervals in order to avoid considerable lengths of fibers to be produced which do not come up to crimping specifications.

The present invention relates to a process and device for compression crimping and more specifically for the automatic control of the crimping arc in fiber strands for spinning. In this process, the ratio of the speed of the strand moving out of the crimping device and the speed at which the strand is drawn off by the machine following the crumper is so adjusted, that a certain amount of the fiber will collect on a scale where it is constantly weighed, the deviations from a certain adjusted value being used for the regulation of the crimping pressure in the crimping chamber.

The process is based on the fact that a smooth strand entering into the crimping device is shortened by the crimping process. The amount of the shortening corresponds to the degree of crimping which is expressed by the ratio of smooth strand and the crimped strand. If the strand leaving the crimping device is passed on to the machine drawing it off, which is usually a cutting device, the latter has to run more slowly than the crimping device in accordance with the ratio above specified. When a constant crimping pressure and a constant crimping degree are used, the length of strand between the two devices is at all times the same; if the crimping pressure is changed, the height of the individual crimping arcs is likewise changed, which also alters the arc number and thereby the degree of crimping.

Since, however, the ratio of speeds of the two machines remains the same, the change in the degree of crimping is shown by the fact that a different length of strand than heretofore will be between the two machines. If, with a constant degree of crimping, for instance, the strand between the two machines exhibits a certain slack, the magnitude of the slack changes in accordance with the changing degree of crimping. The slack becomes smaller as the degree of crimping increases and

2

the slack becomes larger, as the crimping degree decreases.

In accordance with the present invention, the change in lengths of the strand between the two machines may 5 also be made recognizable in another manner, and it may at the same time be used for the automatic regulation of the degree of crimping and of the arc number associated therewith. If, for instance, the crimped strand emerging from the crimping device is first allowed to drop into a 10 container where a certain amount is stored, the cutting machine will, with a constant degree of crimping being maintained, draw off exactly the same lengths as delivered by the crimping device. The stored amount in the container does not change in weight. When the container

15 is placed on the scale, the indicator of the latter will invariably point at the same mark. If at this time the crimping pressure is increased, the degree of crimping will rise, i. e. the crimped strand will be comparatively shorter than before. Since, however, the speeds of both 20 machines are not changed, the cutting machine moves comparatively too fast, that is to say, it pulls off a longer strand than the one delivered from the crimping device. Consequently, the content of the container decreases and the scale shows reduction in weight.

25 In the opposite case, when a larger strand length is delivered by the crimping device than pulled off by the cutting machine, the scale will indicate an increase in weight of the stored fiber and this will correspond to a decrease in the degree of crimping.

30 According to the present invention, the admissible range in the variation of the crimping degree is measured by the use of two limit marks on the graduated plate of the scale; when the indicator reaches these limit marks, a servomotor is actuated which controls the crimping pressure in the crimping device.

In the accompanying drawing, a device according to the invention for carrying out the process heretofore described is illustrated by way of example in a preferred embodiment. It should, however be understood, that the 40 example is given by way of illustration and not by limitation and that many changes in the details may be made without departing from the spirit of the invention.

A smooth strand indicated at 1 is introduced into a 45 compression chamber 3 by means of two feeding rollers 2. The exit opening from the chamber is closed at first, for instance by a flap 12 in the sidewall of the chamber which is spring-controlled by a spring 13. With flap 12 in closed position, chamber 3 will be filled up until by 50 further filling the contents are compressed. This will continue until the pressure in the chamber reaches a degree that will allow it to overcome the counter-pressure of spring 13, so that the chamber opens up. An equilibrium will be formed between the crimping pressure inside and the spring pressure outside and on this equilibrium the degree of crimping will depend. A screw 14 is provided for the adjustment of the pressure operating as crimping pressure. The regulation of screw 14 is controlled by a servomotor 15, coupled with the screw.

55 The crimped strand 4 emerges from the crimping chamber and drops into a container 5 where it forms a stored amount 6, which is drawn off by a pair of rollers 7. Container 5 is disposed on the platform of a scale 8. The scale has an indicator 9 movable on a graduated plate 10, which has two limit marks 11.

60 The pivoted end of indicator 9 is connected to one pole of a weak current source S, whose other pole is connected to a conventional electrical or pneumatic relay A. Arranged between the relay A and the motor 15, is a current source 20. The power source S is capable of 65 changing the direction of rotation of the motor 15 by reversing the polarity of the current source 20.

70 As soon as indicator 9 reaches one of the marks, the

servomotor 15 is actuated in a manner known per se, by the relay means A. The servomotor will then turn screw 14 to advanced or retracted position. Since this screw has only to be turned by slight degrees, motor 15 is coupled thereto with a large transmission.

Furthermore, known means of the measuring technique are used for searching the position of indicator 9 with respect to marks 11 in certain intervals, and to adjust servo motor 15 so that it will run only for a short time, which can be chosen as required, in order to make only a small turn in the adjustment of screw 14. This time, during which the motor is running, will be shorter than the time interval between two search operations of indicator 9.

Between the rollers 7 and the feed rollers 2, a metering device 16 is arranged for measuring the speed, with which the strand enters the pair of rollers 7. The meter 16 indicates the quotient in crimping degrees. One way in which this can be done is to arrange a D. C. dynamo to be driven by the pair of feed rollers 2 and another D. C. dynamo driven by rollers 7. The voltages generated by the two dynamos are transmitted in opposite directions to the meter 16, which in this case is a volt-meter. Since this meter indicates the ratio of the two voltages which are in direct proportion to the R. P. M. of the roller pairs 2 and 7, the scale of the volt-meter 16 can be calibrated to indicate directly the degree of crimping. According to the indicated degree, the ratio of the top speeds of the rollers can be adjusted as required in any particular case.

Example

A strand composed of 28,000 fibers of a titre of 3.75 per fibril is fed in between rollers 2. The rollers are driven at 150 m./min. The chamber 3 has a capacity of 100 cm.³. The pressure which is brought to bear on wall 12 of chamber 3 is adjusted to 40 kg./cm.².

As soon as 3 meters of the strand have been fed into chamber 3, the pressure inside will have increased to an amount which causes spring 13 to move to the right-hand side (in the drawing) and will open the exit at the bottom of chamber 3. The crimped strand will then have 18 crimping arcs per 1 cm. on the average.

As the strand 4 descends from chamber 3, it is collected in container 5 on scale 8. From there the strand is drawn off by a pair of rollers 7 which are driven at 125 M. P. M.

The instrument 16 indicates—in degrees of crimping—the rates of the speeds of roller systems 2 and 7.

A change in pressure is automatically effected by the weight of the accumulation 6 of strand 4 when required. The mechanism for effecting that change operates as above described by means of motor 15 and screw 14 acting on spring 13.

What I claim is:

1. A process for the continuous control of the crimping arc in compression crimping of fiber strands, which comprises crimping said strands in one operation, withdrawing said strands in crimped condition, maintaining a definite ratio between the feeding of the uncrimped strand and the withdrawing thereof in crimped condition, allowing an amount of the crimped strand to collect for weighing the same, and using the deviations in weight from an adjusted value for regulating the crimping pressure in said crimping operation.

2. A device for the continuous control of the crimping arc in compression crimping of fiber strands which comprises a crimping chamber with intake means for said strands, means for exerting a determined crimping pressure on the strands, means for withdrawing said strands after crimping from said chamber, weighing means interposed between the crimping chamber and the withdrawing means, and control means for maintaining a definite ratio between the feeding of the uncrimped strand to said crimping chamber and the withdrawing thereof in crimped condition, the amount of the crimped strand collected on the weighing means being operative in regulating the crimping pressure exerted on the strand in the crimping chamber.

3. A device according to claim 2 wherein a metering device is interposed between said intake means and said withdrawing means of the strand, said metering device indicating the degree of crimping which serves as a directing means for adjusting the ratio of speeds between intake and withdrawal means.

4. A device according to claim 2 including a scale having a platform and an inclined slide for collecting the strand thereon.

5. A device, according to claim 4, wherein the weighing means includes a graduated plate having two limit marks, and an indicator movable over said graduated plate, means being associated with said indicator becoming operative, when said indicator passes beyond said marks, in actuating a servo motor for control of said pressure exerting means associated with said crimping chamber.
